UNITED STATES PATENT OFFICE

160,430

CLOCK OR THE LIKE

Joseph F. Punzak, Brooklyn, N. Y., assignor to United Metal Goods Manufacturing Co., Inc.,
Brooklyn, N. Y., a corporation of New York

Application April 21, 1949, Serial No. 2,174

Term of patent 7 years

(Cl. D42—7)

To all whom it may concern:

Be it known that I, Joseph F. Punzak, a citizen of the United States, residing at Brooklyn, in the county of Kings and State of New York, have invented a new, original, and ornamental Design for Clock or the like, of which the following is a specification, reference being had to the accompanying drawing, forming part thereof.

The figure is a front perspective view of a clock, showing my new design.

I claim:

The ornamental design for a clock or the like, as shown.

JOSEPH F. PUNZAK.
